UNITED STATES PATENT OFFICE

WILLIAM H. NUTT, OF NEWBURYPORT, AND NORWOOD H. KNOWLTON, OF ROCKPORT, MASSACHUSETTS, ASSIGNEES TO UNITED SHOE MACHINERY CORPORATION, OF PATERSON, NEW JERSEY, A CORPORATION OF NEW JERSEY

MACHINE FOR TRIMMING HEEL COVERS

Application filed December 31, 1929. Serial No. 417,764.

This invention relates to trimming machines and is herein illustrated as embodied in a machine designed for trimming heel covers attached to the heels, preparatory to 5 tucking the marginal portions of the covers into grooves in the heels.

When heels are covered in a manner described in United States Letters Patent No. 1,704,204 (issued March 5, 1929, on an application filed in the name of William H. Nutt, 10 relatively narrow grooves are formed in the breast of the heel adjacent to the breast edges of the heel thereby forming a rib extending along each marginal portion of the heel breast. The cover for the rear portion and the sides of the heel is then so applied to the heel that it extends beyond the breast edges, the portions of the cover extending beyond the breast edges are next trimmed so that 15 they still extend a predetermined distance beyond the breast edges, and finally the marginal portions are folded over the ribs of the breast of the heel and are tucked into and secured within the above-mentioned grooves in 20 the breast of the heel. In order to complete the covering of the heel, the portion of the breast between the ribs is covered by a separate piece of material, the lateral margins of which are tucked into and secured within 25 the grooves beside the tucked-in margins of the side cover. In covering the improved heels, it will be clear that the side cover must be trimmed accurately in order that its marginal portions can be fitted properly into the 30 grooves. It is difficult to trim the forward marginal portions of the rear and side covers of heels by hand and such a process is slow and requires a high degree of skill on the part of the operator. Moreover, when the heel 35 covers are trimmed they are usually in temper and if trimmed exactly to the same size as the portion of the heel with which they are to engage they will sometimes be too short to fit accurately into the grooves. It is therefore preferable to allow for shrinkage by 40 trimming the covers slightly oversize and this adds to the difficulty of carrying out the operation by hand.

An object of the present invention is to 45 provide an improved machine which will be

effective and reliable for trimming side covers of heels for reception in grooves such, for example, as disclosed in the above-referred-to Nutt patent.

In accordance with a feature of the present invention the illustrated machine comprises a cutter and a shear member constructed and arranged to trim a cover attached to a heel to prepare a marginal portion of the cover for insertion in a groove in the breast of the heel as the heel is moved past the cutter, a gage for engaging the heel within the groove and a rest for engaging a side of the heel, the gage and the rest being constructed and arranged to position the heel 55 relatively to the cutter for performing the trimming operation, thereby providing an organization for expeditiously trimming heel covers attached to heels.

The cutter and the shear member of the 60 illustrated machine, in accordance with another feature of the invention, are of the rotary type and overlap each other to form a shear couple for trimming the heel cover. The shear member of the illustrated machine 65 may be positively rotated or it may be driven by frictional contact with the rotary cutter depending upon the shear couple operation desired for most effectively severing the material being trimmed. In order to trim 70 covers for reception in grooves located at different distances from the breast edges of the heel and in accordance with another feature of the invention the gage and the rest are mounted for adjustment relatively to the 75 cutter and relatively to each other. The heel-engaging portion of the gage, in accordance with a further feature of the invention, is illustrated as a wheel, surfaces of which are constructed and arranged to engage inside and outside breast edges of the 80 groove in the breast of the heel, the surface which engages the inside breast edge of the groove being inclined at a slight angle to the plane of rotation of the wheel to prevent 85 the wheel from riding out of the groove during the cover trimming operation.

In accordance with a further feature of the invention, the rotary cutter and the rotary shear member of the illustrated machine 90

are urged together and the shafts upon which these members rotate are slightly inclined to each other in order effectively to trim the cover material.

6 The machine illustrated as embodying the invention will now be described with reference to the drawings in which,

10 Fig. 1 is a front elevational view of the illustrated machine which comprises right and left trimming units for trimming the right and left marginal portions of side covers attached to heels preparatory to tucking the marginal portions of the covers into heel cover-receiving grooves in the breasts of the heels;

15 Fig. 2 is a perspective view of the right-hand trimming unit of the machine illustrated in Fig. 1 as seen when looking in the direction indicated by the arrows II—II of Fig. 1;

20 Fig. 3 is an elevational view of the left end of the right-hand trimming unit illustrated in Fig. 1;

25 Fig. 4 is a detail view illustrating portions of the mechanism for adjusting the heel-positioning gage of the unit illustrated in Figs. 2 and 3 relatively to the rotary cutter shown in that unit;

30 Fig. 5 is a sectional view of the illustrated machine taken along the line V—V of Fig. 3 clearly to show the mounting of a rotary shear member which cooperates with the rotary cutter to form a shear couple for trimming heel covers;

35 Fig. 6 is a perspective view showing the relative positions of the heel, the cover of which is being trimmed, and the heel positioning and trimming instrumentalities illustrated in Figs. 2 and 3 of the drawings;

40 Fig. 7 is another view of the heel and the heel-positioning and trimming instrumentalities illustrated in Fig. 6 as seen when looking in the direction indicated by the arrows VII—VII of Fig. 6, the heel and a portion of the machine being shown in section; and

45 Fig. 8 is a detail view illustrating the construction of the heel-engaging portion of the gage in guiding contact with the sides of a groove in the breast of the heel.

50 The illustrated machine comprises a cutter 20 and a shear member 22 in overlapping relation and constructed and arranged to trim a cover 24 attached to a heel to prepare the marginal portions 26, 27 of the cover 24 for insertion in grooves 28 in the breast of the heel as the heel is moved past the cutter, a gage 30 constructed and arranged to engage the heel within the groove 28 and a rest 32 for engaging a side of the heel, the gage 30 and the rest 32 being adapted to position the heel and the heel cover relatively to the cutter for performing the trimming operation.

55 In order that the operator may trim the cover 24 along each of the marginal portions

26 and 27 thereof starting at the tread end portion 34 (Fig. 6) of the cover and finishing at the attaching face end 36 of the cover as he moves the heel rearwardly of the machine, the illustrated construction (Fig. 1) comprises right and left units A and B, respectively. It will be necessary, however, to describe but one of the units since the parts in each of these units are identical, the only difference in construction of the units A and B being in the reversal of some of the parts thereof for trimming the marginal portions 26, 27, respectively, of the cover. In order to support the units A, B at a height convenient for presenting the work to the heel-positioning and trimming instrumentalities, the illustrated machine is provided with a pair of laterally extending plates 38 (Fig. 1) supported upon and bolted to a block 40 which may be adjustably mounted in a vertical direction upon a standard 42. The heel-positioning and trimming instrumentalities of each of the units are supported in a housing 44 having a flanged base plate 46 which is bolted to the plate 38.

90 The housing 44 comprises a pair of upstanding ears 48 each of which is bifurcated to receive bearings 50, 52 for the shafts 54, 56 respectively, upon the ends of which shafts 54, 56 are mounted the rotary cutter 20 and the shear member 22, respectively which form a cover shear couple. The cutter-shaft 54 is operated by a pulley 58 rotatably mounted upon the outer end of the shaft 54 and connected through a belt 60 to a driving pulley 62 (Fig. 1) which is also the source of power for operating the shear member 22 as will soon appear in the following description of the machine. When operating upon certain grades of leather and celluloid it may be desirable positively to rotate the shear member 22 rather than to have its rotation dependent upon frictional contact with the cutter 20. The machine is thus constructed and arranged so that the shaft 56 may be alternatively driven through frictional contact with the cutter 20 or may be positively driven through the cutter-shaft 54. Mounted upon the cutter-shaft 54 is a skew gear 64 constructed and arranged to mesh with a skew gear 66 keyed to the top portion 68 of a vertically disposed shaft 70, the lower end of which is journaled in a bearing 72 of a removable block 74 and the top portion 68 of which is held in vertical position through a removable pin 76 which fits into a bore 78 of a depending portion 80 of a cover 82 and engages within a recess 84 in the end of the shaft 70. The lower portion of the shaft 70 between the gear 66 and the block 74 has a worm 86 thereon which meshes with a skew gear 88 carried by the shaft 56. It will be clear that when the pin 76 has been removed from the recess 84 of the shaft 70 that after loosening a set-screw 89, the block 74 to-

gether with the shaft 70 and the gear 66 may be removed from the machine, thus throwing the shaft 54 out of positive rotation with the shaft 56.

The cutter-shaft 54 is fixed against longitudinal movement in its bearings and the shaft 56 which carries the shear member 22 may be moved slightly lengthwise thereof in order that its face 90 (Fig. 7) may be constantly urged toward the face 92 of the cutter 20. The contact of the cutter 20 and the shear member 22 is assured by employing a bell crank lever 94 (Figs. 1 and 5) pivoted in a bracket 96 screwed to the housing 44 and having a vertically disposed arm 98 provided with a recessed portion 99 (Fig. 5) which engages a ball bearing 102 seated in a recess 104 at the end of the shaft 56. A spring 106 seated in a bore 108 and acting against the lower arm 110 of the bell crank lever 94 constantly urges the arm 98 against the shaft 56 thus forcing the face 90 of the shear member 22 toward the face 92 of the cutter 20. In order to assure that the cutting portions 25 of the shear couple at the point of entry 112 (Fig. 2) of the couple will engage each other under substantial pressure and thus operate more effectively, the shaft 56 is mounted for slight angular adjustment relatively to the cutter-shaft 54 in a horizontal plane (Fig. 5). When such an adjustment has been made it is clear that the planes of rotation of the rotary cutter 20 and the shear member 22 will be inclined to each other. The mechanism for carrying out this adjustment will 30 now be briefly described. The shaft 56 is mounted in the above-mentioned bearings 52 which taper from their ends 114 toward their central portions 116 and may be swung in a horizontal plane relatively to the cutter-shaft by operating the screws 118. Each of the screws 118 carries a lock-nut 120 for securing its respective screw 118 in place after the shaft 56 has been properly aligned.

45 The operative parts located between the upstanding ears 48 of the machine are protected from grit and dirt by the above-referred-to cover 82 which may be bolted to the top of the machine and by side plates 50 122 having slots 124 for receiving the screws 126 and through which the plate is clamped to and removed from the housing 44.

In order accurately to present a heel having a cover 24 attached thereto to the cutter 20 and the shear member 22 for the purpose already explained, the gage 30 and the rest 32 are constructed and arranged for adjustment relatively to the trimming instrumentalities. The gage 30 is carried by a rod 128 which is slidable in an arm 130 and has a slot 132 (Fig. 2) in its upper surface for receiving a flared portion 134 of a screw 136 carried by the arm 130. In order to raise or lower the rod 128, the arm 130 has a set-screw 138 in threaded engagement therewith,

the end of which set-screw normally abuts against a beveled portion 140 of the rod 128 and may be turned to release the rod 128 for movement relative to the arm 130. After the rod 128 has been released the screw 136 ⁷⁰ is turned until a proper adjustment is effected after which the set-screw 138 is turned so that it engages the beveled portion 140 of the arm. For adjusting the rod 128 and the arm 130 as a unit in the direction indicated by arrows 142 (Figs. 2, 4) relatively to the cutter 20, the arm 130 is provided with a slot 144 (Fig. 4) which straddles a stud 146 screwed into a lug 148. After releasing a flange 150 of the stud 146 from engagement ⁷⁵ with the face 151 of the arm 130 and after relatively adjusting the arm 130 and the lug 148 by turning a screw 154, the arm 130 is again clamped between the flange 150 and the lug 148 to set the arm 130 and the lug 146 ⁸⁰ in adjusted relative positions. The foregoing relatively adjusted members are mounted for adjustment in the general plane of the cutter in a direction indicated by arrows 156 (Fig. 2) upon a ribbed upper surface 158 ⁸⁵ of a block 160 which is bolted to the top of the housing 44. The under surface 162 of the base portion 164 of the lug 148 has a shape complementary to ribbed upper surface 158 of the block 160 and may be clamped thereto by ⁹⁰ a threaded stud 166 which passes through a slot 168 in the base of the lug and has a flange 170 which engages the top surface of the base portion 164 for clamping it to the block 160. ⁹⁵

The rest 32, which engages the heel adjacent to one of the breast edges 172 of the heel (Fig. 7) and cooperates with the gage 30 in positioning the cover 24 attached to the heel relatively to the shear couple, comprises ¹⁰⁰ 105 an elongated curved surface 174 for protecting the operator from the shear couple. In order to adjust the rest 32 (Figs. 2 and 3) relatively to the shear couple in directions indicated by the arrows 176, 178 and 180, the machine is provided with three tongues and ¹¹⁰ complementary channel couplings 182, 184 and 186, respectively, which may be loosened and tightened for purposes of adjustment by the screws 188, 190 and 192, respectively, as will ¹¹⁵ be clear upon inspection of Fig. 2 of the drawings.

Provision is also made for sharpening the cutter 20 without removal of the same from the machine. As best illustrated in Figs. 2 ¹²⁰ and 3 of the drawings, a grinding wheel 194 mounted upon a plunger 196 extends through a cylindrical member 198 having a projecting portion 200 journaled in a bearing 202 at one end of a bracket 204. The other end of the bracket 204 is mounted for swinging movement about a rod 206 supported from the housing 44. The bracket 204 is normally held in the position illustrated in Fig. 3 away ¹²⁵ from the cutter by a coil spring 208 mounted ¹³⁰

upon the rod 206 and having its ends 210, 212 secured to the housing 44 and in a tail-piece 214 of the bracket 204, respectively. It is clear from the above description that the 5 grinding wheel 194 may be conveniently moved from its inoperative position shown in Fig. 3 into its operative position shown in Fig. 2 for sharpening the cutter and that the grinder will normally assume its inoperative 10 position.

During the trimming operation, it has been found that there is sometimes a tendency for the portion 216 (Fig. 6) of the cover 24 which has been trimmed to become wound 15 around one of the rotating shafts 54 or 56 with the result that portions of the side cover are torn from the heel. In order to avoid this difficulty, the machine is provided with stationary sleeves 218, 220 for covering the cutter-shaft 54 and the shaft 56, respectively. The sleeve 218 has a flared portion 222 secured to the bearing 50 (Fig. 2) and the sleeve 220 is sweated into a block 224 which has two pins 226 extending therethrough for engaging 20 a slot 228 in the bearing 52 for supporting the sleeve 220. In order to adjust the sleeve 54 lengthwise of the shaft 56 each of the pins 226 is mounted for sliding movement in the block 224 and may be locked 25 to the block by a set-screw 230.

It will be noted (Fig. 8) that the portion of the gage 30 which engages the heel is illustrated as a wheel 232 mounted for rotation upon the rod 128. The wheel is constructed and arranged to enter the groove and has two faces 234, 236 for engaging the inside and outside breast edges 238, 240 of the groove 28. The face 234 is inclined at a steeper angle to the axis of rotation than 30 is the face 236 of the wheel, the reason for the steep inclination of the face 234 to the axis of rotation being to prevent the wheel 232 from riding out of the groove 28 at the upper convex portion 242 of the breast of the heel 45 by contact with a portion of the breast located at a point removed from the breast edge 238 of the groove.

The operation of the machine is as follows. The machine is first adjusted in order to set 50 the gage 30 and the rest 32 at their proper positions relatively to the shear couple and the machine is arranged either positively to drive the shear member 22 or to drive said member through frictional drag of the cutter 55 20. The operator then manually moves the heel away from him (Fig. 6) with the gage 30 engaging within the groove 28, the side of the heel adjacent to the breast edge thereof (Fig. 7) engaging the rest 32, the trimming 60 cut progressing from the tread end 34 of the heel to the attaching end 36 thereof. The right and left marginal portions of the cover are trimmed in units A and B, respectively, 65 it being immaterial which portion is first trimmed.

Having thus described the invention, what we claim as new and desire to secure by Letters Patent of the United States is:

1. A trimming machine having, in combination, a shear couple, a gage constructed and arranged to engage a heel within a groove in the breast of the heel, and a rest for engaging a side of the heel, said gage and rest being constructed and arranged to position the heel relatively to the shear couple for trimming a marginal portion of a cover attached to the heel for insertion in said groove as the heel is moved past the shear couple. 70

2. A trimming machine having, in combination, a shear couple, a gage constructed and arranged to engage the breast edges of a groove in the breast of a heel, and a rest for engaging a side of the heel, said gage and rest being constructed and arranged to position the heel relatively to the shear couple for trimming a marginal portion of a cover attached to the heel for insertion in said groove as the heel is moved past the shear couple. 80

3. In a trimming machine, a rotary cutter, a shear member arranged to support a cover attached to a heel and to cooperate with the cutter for feeding the cover between the cutter and the shear member and for trimming the cover to prepare a marginal portion thereof for insertion in a groove in the breast of a heel as the heel is moved past the cutter, and a gage constructed and arranged to engage within the groove for facilitating the positioning of the heel relatively to the cutter and the shear member. 90

4. In a trimming machine, a rotary cutter, a rotary shear member arranged to support a cover attached to a heel and to cooperate with the cutter for feeding the cover between the cutter and the shear member and for trimming the cover to prepare a marginal portion thereof for insertion in a groove in the breast of a heel as the heel is moved past the cutter, and a gage constructed and arranged to engage within the groove for facilitating the positioning of the heel relatively to the cutter and the shear member. 105

5. In a trimming machine, a rotary disk cutter, a rotary shear member arranged to support a cover attached to a heel and to cooperate with the cutter for feeding the cover between the cutter and the shear member, a gage constructed and arranged to engage the heel within a groove in the breast of the heel, and a rest for engaging a side of the heel, said gage and rest being positioned in predetermined relation to each other for positioning the heel relatively to the cutter and the shear member for trimming a marginal portion of a cover attached to the heel for insertion in said groove as the heel is moved past the cutter. 115

6. In a trimming machine, a rotary disk cutter, a shear member mounted for movement under the frictional pull of the cutter 120

and constructed and arranged to support a cover attached to a heel and to cooperate with the cutter for feeding the cover between the cutter and the shear member, a gage constructed and arranged to engage a heel within a groove in the breast of the heel, and a rest for engaging a side of the heel, said gage and rest being positioned in predetermined relation to each other for positioning the heel relatively to the cutter and the shear member for trimming a marginal portion of a cover attached to the heel for insertion in said groove as the heel is moved past the cutter.

7. In a trimming machine, a rotary cutter, a rotary shear member having a portion overlapping the cutter for rotating the member by the frictional drag of the cutter, said member being constructed and arranged to support a cover attached to a heel and to cooperate with the cutter for feeding the cover between the cutter and the shear member, a gage constructed and arranged to engage the heel within a groove in the breast of the heel, and a rest for engaging a side of the heel, said gage and rest being positioned in predetermined relation to each other to position the heel relatively to the cutter and the shear member for trimming a marginal portion of the cover for insertion in said groove as the heel is moved past the cutter.

8. In a trimming machine, a rotary cutter, a rotary shear member constructed and arranged for rotation by the frictional drag of the cutter, means for setting the machine positively to rotate the shear member, said shear member being constructed and arranged to support a cover attached to a heel and to cooperate with the cutter for feeding the cover between the cutter and the shear member and for trimming the cover to prepare a marginal portion thereof for insertion in a groove in the breast of the heel as the heel is moved past the cutter, a gage constructed and arranged to engage the heel within the groove, and a rest for engaging a side of the heel, said gage and rest being positioned in predetermined relation to each other for positioning the heel relatively to the cutter and the shear member during the heel trimming operation.

9. A trimming machine having, in combination, a shear couple, a gage constructed and arranged to engage a heel within a groove in the breast of the heel, and a rest for engaging a side of the heel, said gage and rest being constructed and arranged to position the heel relatively to the shear couple for trimming a marginal portion of a cover attached to the heel for insertion in said groove as the heel is moved past the shear couple, said cutter, gage and rest being mounted for relative movement to adjust the machine for operating upon different sizes and styles of heels.

10. A trimming machine having, in combination, a cutter, a shear member, a gage for engaging a heel within a groove in the breast of the heel, and a rest for engaging a side of the heel, said gage and rest being positioned in predetermined relation to each other to position the heel relatively to the cutter and the shear member for trimming a marginal portion of a cover attached to the heel for insertion in said groove as the heel is moved past the cutter, the gage and the rest being mounted for movement relatively to the cutter and shear member to adjust the machine for operating upon different sizes and styles of heels.

11. In a trimming machine, a cutter, a shear member constructed and arranged to trim a cover attached to a heel to prepare a marginal portion of the cover for insertion in a groove in the breast of the heel as the heel is moved past the cutter, a gage constructed and arranged to engage a heel within a groove in the breast of the heel, and a rest for engaging a side of the heel, said gage and said rest being mounted for movement relatively to the cutter and the shear member and also being mounted for movement relatively to each other in order accurately to adjust the machine for operating upon heels of different sizes and styles.

12. In a trimming machine, a rotary cutter, a shear member mounted for rotation by the frictional drag of the cutter, said member being constructed and arranged to support a cover attached to a heel and for cooperating with the cutter for feeding the cover between the cutter and the shear member as well as to trim the cover for preparing a marginal portion thereof for insertion in a groove in the breast of the heel as the heel is moved past the cutter, a gage constructed and arranged to engage the heel within the groove to position the heel relatively to the cutter and the shear member, and means for setting the machine positively to rotate the shear member.

13. A machine for trimming heel covers having, in combination, a rotary disk cutter and a rotary shear member constructed and arranged to trim a cover attached to a heel to prepare a marginal portion of the cover for insertion in a groove in the breast of the heel, a gage constructed and arranged for positioning between the covering and the heel and having a portion for engaging the heel within the groove, and a rest for engaging a side of the heel and for cooperating with said gage in positioning the cover relatively to the cutter and the shear member.

14. A machine for trimming heel covers having, in combination, a rotary disk cutter and a rotary shear member constructed and arranged to trim a cover attached to a heel to prepare a margin of the cover for insertion in a groove in the breast of the heel, a

- gage constructed and arranged for positioning between the cover and the heel and having a portion for engaging within the groove, and a rest for engaging a side of the heel and 5 for cooperating with said gage to position the cover relatively to the cutter, the gage and the rest being mounted for adjustment relatively to the cutter and relatively to each other to adjust the machine for operating 10 upon heels of different sizes and styles.
15. In a trimming machine, a rotary disk cutter, a rotary shear member arranged to support a cover attached to a heel and to cooperate with the cutter for feeding the cover 15 between the cutter and the shear member for trimming the cover to prepare a marginal portion thereof for insertion in a groove formed in the breast of the heel, a gage comprising a rotatably mounted member having a convex 20 surface constructed and arranged to engage the heel and to be received within the groove, and a rest for engaging a side of the heel, said gage and rest being positioned in predetermined relation to each other for positioning 25 the heel relatively to the cutter and the shear member during the heel trimming operation.
16. A machine for trimming covers having, in combination, means for trimming a cover attached to a heel to prepare a marginal portion 30 of the cover for insertion in a groove in the breast of the heel, and a gage comprising a rotatably mounted member surfaces of which are inclined at different angles to the plane of rotation constructed and arranged to 35 engage opposite breast edges of the groove for positioning the cover relatively to the trimming means as the heel is moved past the trimming means.
17. A trimming machine having, in combination, means for trimming a cover attached 40 to a heel to prepare a marginal portion of the cover for insertion in a groove in the breast of the heel, and a gage comprising a rotatably mounted member surfaces of which are 45 constructed and arranged to engage inside and outside breast edges of the groove for positioning the cover relatively to the trimming means, the surface which engages the inside breast edge of the groove being inclined 50 at a slight angle to the plane of rotation of the member to prevent the member from riding out of the groove as the heel is moved past the trimming means.
18. A machine for trimming covers having, 55 in combination, a rotary disk cutter and a rotary shear member constructed and arranged to trim a cover attached to a heel to prepare a marginal portion of the cover for insertion in a groove in the breast of the heel, a gage comprising a rotatably mounted member 60 the sides of which are inclined at different angles to the plane of rotation constructed and arranged to engage opposite breast edges of the groove, and a rest for engaging 65 a side of the heel and for cooperating with

said gage to position the cover relatively to the cutter.

19. A trimming machine having, in combination, a rotary shear couple mounted upon rotating shafts, means for positively rotating 70 said shafts, means for guiding a heel past the rotary shear couple for trimming a cover attached to the heel, and means for preventing a portion of the cover being operated upon from winding around the shafts during rotation of the same. 75

20. A trimming machine having, in combination, a rotary couple mounted upon rotating shafts, means for guiding a heel past the rotary couple for trimming a cover attached 80 to the heel, and sleeves surrounding the portion of the shafts adjacent to the said couple constructed and arranged to prevent trimmed portions of the cover from winding 85 around the shafts.

21. A machine for trimming heel covers having, in combination, a disk cutter and a shear member mounted upon rotating shafts and constructed and arranged to cooperate with each other for trimming a cover attached to a heel to prepare a marginal portion of the cover for insertion in a groove in the breast of the heel, stationary sleeves for covering portions of the rotating shafts adjacent to the cutter and the member, a gage 90 constructed and arranged for positioning between the cover and the heel and having a portion for engaging within the groove, and a rest for engaging a side of the heel and for 95 cooperating with said gage to position the cover relatively to the cutter.

22. A trimming machine having, in combination, a rotary disk cutter, a rotary disk shear member, means for guiding a heel past the cutter and the shear member for trimming a cover attached to the heel, and means for urging the cutter and the shear member toward each other, said cutter and shear member having their respective planes of rotation inclined to each other to assure contact of the cutter and the shear member at the point of entry of the cover between the cutter and the shear member. 100

23. A trimming machine having, in combination, a rotary disk cutter, a rotary disk shear member, means for guiding a heel past the cutter and the shear member for trimming a cover attached to the heel, means for urging the cutter and the shear member toward each other, said cutter and shear member having their respective planes of rotation inclined to each other to assure contact of the cutter and the shear member at the point of entry of the cover between the cutter and the shear member, and means for varying the inclination of the plane of rotation of the cutter and the plane of rotation of the shear member. 115

In testimony whereof I, the said WILLIAM H. NUTT, have signed my name to this specification.

WILLIAM H. NUTT.

5 In testimony whereof I, the said NORWOOD H. KNOWLTON, have signed my name to this specification.
